(57) CLAIM

I claim the ornamental design for a prayer medallion, as shown and described.

DESCRIPTION

FIG. 1 is a frontal view of the prayer medallion according to the present design;

FIG. 2 is a right side view of the present design, a corre-

FIG. 3 is a top view of the present design; and,

FIG. 4 is a bottom view of the present design.

It being understood that the broken lines are for illustrative purposes only.
